UNITED STATES PATENT OFFICE.

MARCUS P. EXLINE, OF DALLAS, TEXAS.

IDENTIFICATION DEVICE FOR TOOTHBRUSHES.

Application filed May 22, 1925. Serial No. 32,080.

To all whom it may concern:

Be it known that I, MARCUS P. EXLINE, a citizen of the United States, residing at Dallas, in the county of Dallas and State of Texas, have invented certain new and useful Improvements in Identification Devices for Toothbrushes; and I do hereby declare the following to be a full, clear, and exact description of the invention, such as will enable others skilled in the art to which it appertains to make and use the same.

This invention relates to a device for identifying articles, such as tooth brushes, by means of which confusion with similar articles may be avoided.

The object of the present invention is to provide identifying means which may be economically manufactured with a variety of identifying marks thereon and applied without tools and in a simple and permanent manner to the articles to be identified.

In this manner tooth brushes, for instance, may be provided with an identifying member bearing distinctive indicia to be selected by a customer from a variety of brushes in the druggist's stock and quickly and permanently applied without tools.

By means of this invention, the choice of brushes is increased, while at the same time suitable identifying marks may be applied as desired to the particular brush selected.

The invention consists of the novel construction, arrangement and combination of parts as hereinafter and more particularly described and claimed.

One sheet of drawings accompanies this specification as part thereof, in which like reference characters indicate like parts throughout.

Fig. 1 is a perspective view of a tooth brush showing an improved identifying member in position.

Fig. 2 is a fragmentary perspective view of a part of the handle preliminary to applying the identifying member.

Fig. 3 is a longitudinal cross sectional view through a handle showing the identifying member in its initial position preliminary to being secured on the handle.

Fig. 4 is a similar longitudinal cross sec-

tional view through a portion of the handle showing the identifying member in its attached position.

Fig. 5 is a transverse sectional view taken through the handle and through the stud 55 hereinafter described.

Fig. 6 is a bottom plan view of the improved identifying member.

In accordance with the present invention, the handle of the brush is provided with a stud 3, which is preferably integral with the handle and formed by a groove 2 cut or molded in the handle.

The improved identifying member consists of a disk 4 having upon its outer face suitable indicia 5 and having its peripheral edge inturned as at 6 to secure a second disk member 7 provided with a plurality of peripheral prongs, which are normally directed toward the center and outwardly with respect to the major plane of the device. The circle defined by the points of the prongs 8 is of a diameter substantially the same as that of the stud 3 formed in the brush handle. 65 70 75

In operation, the identifying member 4 is applied to the handle with the prongs 8 in engagement with the upper peripheral edge of the stud 3 and then pressed into the groove 2, thereby forcing the prongs 8 over the stud 3 and modifying their angular relation so that they point toward the center, but inwardly and upwardly toward the major plane of the device whereby withdrawal of the identifying member is rendered impractical without mutilating the handle. 80 85

Various modifications in the number, shape and structure of the identifying member may be made without departing from the spirit of the present invention, as specified in the claims. 90

Having thus described my invention, I claim:

1. The combination of an article having a stud defined by a surrounding groove and an identifying member comprising a plate with a down turned peripheral flange adapted to seat in said groove and means for securing the plate to the stud comprising a 95 100

plurality of inwardly directed peripheral prongs carried by the plate adjacent the edge of the flange.

2. The combination of an article having a stud defined by a surrounding groove and an identifying member comprising a plate with a down turned peripheral flange adapted to seat in said groove and means for se-

curing the plate to the stud comprising a plurality of inwardly directed peripheral prongs carried by the plate adjacent the edge of the flange, said prongs bent inwardly toward the plate and into engagement with said stud.

In testimony whereof I affix my signature.

MARCUS P. EXLINE.
